UNITED STATES PATENT OFFICE

2,098,430

FURNACE WALL

Charles L. Myers, Overbrook, Pa., assignor to
American Engineering Company, Philadelphia,
Pa., a corporation of Pennsylvania

Application January 23, 1937, Serial No. 122,014

15 Claims. (Cl. 122—4)

This invention relates to furnace walls, and more particularly to furnace walls of the fluid cooled type.

One object of the present invention is to provide a simplified and generally improved wall of the stated character having particular application to stoker furnaces.

Another and more specific object is to provide improved fluid cooled side and rear walls for stoker furnaces consisting of two sets or series of fluid conducting tubes, each set being so constructed as to extend substantially the length of a side wall, and one-half the width of said rear wall, the rearwardly disposed ends of said sets 15 of tubes terminating in a common header whereby the number of header connections for the tubes is reduced to a minimum.

Other and further objects of the invention will become apparent as the description of the invention progresses.

Of the drawings:

Fig. 1 is a longitudinal view taken through the furnace substantially along line 1—1 of Fig. 2, showing the construction of the fluid cooled walls comprising the present invention.

Fig. 2 is a plan view partly in section, and with portions of the furnace walls removed to show the arrangement of the tubes and headers of the fluid cooled side and rear walls.

Fig. 3 is a fragmentary plan view of a modified header construction for the rear wall of the furnace.

Fig. 4 is a longitudinal view taken through one of the retorts of a stoker furnace showing the invention applied to a stoker of the continuous ash discharge type.

Fig. 5 is a plan view partly in section, and with parts of the furnace walls removed showing the arrangement of the tubes and headers provided 40 in the side and rear walls, and

Fig. 6 is a fragmentary plan view of the upper end of the header provided in the rear wall, showing the manner in which the tubes are attached thereto, and also the protective means for 45 the said header and tubes.

Referring to the drawings, the numeral 1 indicates generally a furnace provided in the present instance with an inclined grate, multiple retort stoker 2 of a well known type. Stoker 2 consists 50 of alternately disposed retorts 3 and tuyère rows 4 to which fuel from hoppers 5 is fed by any suitable feeding mechanism shown generally at 6. Pushers 7 provided in the bottom of each retort 2 feed the fuel to extension grates 8, which in 55 turn feed the fuel to dump grates 9 provided at

the rearmost end of the stoker. The ashes forming on dump grates 9 may be discharged from the stoker by actuating said grates downwardly through a link and lever mechanism 10, after a well known fashion.

The combustion chamber 11 of the furnace is bounded by front and rear walls 12 and 13 respectively, and by side walls 14 and 15. The areas of side walls 14 and 15, and of rear wall 13 adjacent the stoker 2, have recesses provided 10 therein in which are mounted, in any suitable manner, fluid cooled sections 16, 17 and 18 respectively. Fluid cooled section 16 comprises a series of fluid conducting tubes 19 secured at the upper ends thereof to a substantially vertical 15 header 20 mounted, in any suitable manner, exteriorly of front wall 12, and incline downwardly and rearwardly in substantially parallel relation with the stoker 2. The lower ends of tubes 19 are bent through an angle of substantially 90 degrees, as shown at 21, and then extend transversely along rear wall 13 and terminate in a substantially vertical header 22 mounted in any suitable manner in said rear wall substantially 20 midway between side walls 14 and 15. Fluid 25 cooled section 17 also comprises a series of fluid cooled tubes 23 secured at the upper ends thereof to a substantially vertical header 24 also mounted, in any suitable manner, exteriorly of front wall 12, and also inclined downwardly and rearwardly 30 similarly to the tubes 19. The lower portions of these tubes are also bent through an angle of substantially 90 degrees, as shown at 25, and then extend transversely across rear wall 13, and also terminate in header 22. Referring to Fig. 2, it 35 will be noted that the rearwardly disposed ends of the first and second dump grates 9 at each side of the stoker are curved to conform with the curvature of the tubes 21 and 25, so that a uniform support is provided for the ashes across 40 the entire width of the stoker. To protect the tubes 19 and 23 from the abrasive and corrosive action of the fuel any suitable protective blocks 26 may be provided. These blocks may be of the general type shown and described in United 45 States Patent No. 2,002,276, or of any other suitable construction. The header 22 and the portions of the tubes adjacent thereto may also be provided with protective blocks 27, as shown in Fig. 2. Header 22 may be connected to the boiler (not shown) by a downtake connection 28, while headers 20 and 24 may be connected to the boiler by uptake connections 29 and 30 respectively.

From the foregoing description it is seen that simplified, as well as highly improved fluid cooled 55

side and rear wall constructions have been provided. The tubes extending downwardly along the side walls of the furnace are so formed as to also cover an area of the rear wall, and terminate 5 in a common lower header. This not only provides an efficient construction, but eliminates the need for more than one header for the lower ends of the tubes.

It sometimes is desirable to employ a substantially square header in the rear wall, and to this end the construction shown in Fig. 3 is provided. As therein shown it will be noted that the tubes 19' and 23' terminate at the lower ends thereof in a rectangular header 22'. Such an 15 arrangement eliminates an additional bend in the tubes, and simplifies, to a certain extent, the method of attaching protective blocks to the tubes. The header 22', if desired, may be exposed to the furnace heat without a covering of protective material. The protective blocks provided on the tubes 19 and 23 may also be eliminated in certain installations, if it is so desired.

Figs. 4 to 6 inclusive show an alternative construction wherein the invention is applied to a 25 furnace 32 of the continuous ash discharge type. Furnace 32 also comprises a stoker 33 consisting of alternately disposed retorts 34 and tuyère rows 35. Fuel is fed along the stoker by pushers 36 provided at the bottom of each of the retorts to 30 dead plates 37 provided at the lower ends thereof, and thence to reciprocating extension grates 38, which in turn feed the consumed fuel to adjustable dump grates 39 provided at the rearmost end of the stoker. Furnace 32 also comprises front 35 and rear walls 40 and 41 and side walls 42 and 43. In the present instance a portion of the front wall 40 is cooled by a series of fluid conducting tubes 44 extending downwardly from a boiler (not shown). These tubes are then bent 40 so as to overlie the tuyère rows 35, as shown at 45, and then continued downwardly between extension grates 38 and are then bent downwardly and forwardly, as shown at 46, and terminate in a transversely disposed lower header 47 provided beneath the stoker. A second series of 45 tubes 48 extend upwardly from header 47 in substantially parallel relation with tubes 45. These tubes also extend between certain of the extension grates 38, and then continue forwardly, as 50 shown at 49 in cooling relation with dead plates 37, and terminate at their upper, forwardly disposed ends in a second transversely disposed header 50. The side walls 42 and 43 are provided with fluid cooled sections 51 and 52 respectively, 55 while the rear wall 41 is also provided with a downwardly and rearwardly inclined fluid cooled section 53. Fluid cooled section 51 and substantially one-half of section 53 consist of a series of fluid conducting tubes 54 connected at the 60 upper ends thereof to a header 55. These tubes then extend downwardly in substantially parallel relation with the stoker 33, and are then bent through substantially 90 degrees, as shown at 56, and then extend transversely across section 53 in 65 an inclined series, as shown in Figs. 4 and 5, and terminate in a downwardly and rearwardly inclined header 57 provided substantially midway between the ends of the rear wall. Fluid cooled section 52 also comprises a series of fluid conducting tubes 58 secured at the upper ends thereof to a header 59, and also extend downwardly and rearwardly in substantially parallel relation with the stoker. The lower ends of these tubes 70 are also bent through substantially 90 degrees, as shown at 60, and then extend transversely in

an inclined series and terminate in header 57. Any suitable protective blocks 61 may be provided on the tubes 54 and 58, as well as on header 57.

The inclined fluid cooled section 53 is spaced from the lower end of the stoker forming therewith a discharge passage 62 through which the consumed fuel may be fed from the stoker. The discharge end 63 of this passage may be varied in size by adjusting dump plates 39. The dump plates 39, in the present instance, are mounted on a square shaft 64 and may be adjusted by means of a lever 65 secured to one end of said shaft and mounted exteriorly of side wall 42. The lever 65 has a locking detent 68 provided thereon which may enter any one of a series of notches 67 provided in a bracket 69 mounted adjacent lever 65. By such a construction it is seen that the consumed fuel or ashes may be continuously fed from the stoker. A seal is also provided by the ashes, which prevents the infiltration of air during operating periods of the furnace. Header 57 may be connected to a boiler (not shown) by a downtake connection 70 while headers 55 and 59 are respectively connected to the boiler by up-take connections 71 and 72. The headers 47 and 50 disposed beneath the stoker may also be connected to the boiler by downtake and up-take connections 73 and 74 respectively. It therefore is seen that the embodiment of the invention shown in Figs. 4 and 5 is also of a simplified and highly improved construction.

The embodiments of the invention herein described have been shown simply for the purpose of illustration, it being apparent that other and further modifications may be made without departing from the invention. The invention therefore is to be limited only by the scope of the claims which follow.

What is claimed is:

1. In a furnace, having front, rear and side walls, the combination of fluid cooled sections for said side and rear walls comprising, a pair of headers mounted exteriorly of said front wall, a third header mounted intermediate the ends of said rear wall, a series of fluid conducting tubes extending rearwardly from each of said first mentioned headers and lying in substantially abutting relation with the inner surfaces of said side walls, said tubes being bent near their rearwardly disposed ends so as to lie in abutting relation with a portion of the inner surface of said rear wall, and said tubes terminating in said third header.
2. In a furnace, having front, rear and side walls, the combination of fluid cooled sections for said side and rear walls comprising, a pair of headers mounted exteriorly of said front wall, a third header mounted intermediate the ends of said rear wall, a series of fluid conducting tubes extending rearwardly from each of said first mentioned headers and lying in substantially abutting relation with the inner surfaces of said side walls, said tubes being bent near their rearwardly disposed ends so as to lie in abutting relation with a portion of the inner surface of said rear wall, said tubes terminating in said third header, and protective means for said tubes and third header.
3. In a furnace, having front, rear and side walls, the combination of fluid cooled sections for said side and rear walls comprising, a pair of headers mounted exteriorly of said front wall, a third header mounted intermediate the ends of said rear wall, a series of fluid conducting tubes extending rearwardly from each of said first mentioned headers and lying in substantially abutting relation with the inner surfaces of said side walls,

5 said tubes being bent near their rearwardly disposed ends so as to lie in abutting relation with a portion of the inner surface of said rear wall, said tubes terminating in said third header, protective means for said tubes and third header, and means for circulating a cooling medium through said tubes and headers.

10 4. In a furnace having front, rear and side walls, the combination with a stoker, of fluid cooled sections for said side and rear walls adjacent said stoker, said sections comprising a pair of headers mounted exteriorly of said front wall, a third header mounted intermediate said rear wall, and a series of fluid conducting tubes extending rearwardly from each of said first mentioned headers and lying in substantially abutting relation with the inner surfaces of said side walls, said tubes being bent near their rearwardly disposed ends so as to lie in abutting relation with 15 a portion of the inner surface of said rear wall, and said tube terminating in said third header.

20 5. In a furnace, having front, rear and side walls, the combination with a stoker, of fluid cooled sections for said side and rear walls adjacent said stoker, said sections comprising a pair of headers mounted exteriorly of said front wall, a third header mounted intermediate said rear wall, a series of fluid conducting tubes extending rearwardly from each of said first mentioned 25 headers and lying in substantially abutting relation with the inner surfaces of said side walls, said tubes being bent near their rearwardly disposed ends so as to lie in abutting relation with a portion of the inner surface of said rear wall, 30 said tube terminating in said third header, and means provided on said tubes and third header protecting the same against the abrasive and corrosive action of the fuel fed by said stoker.

35 6. In a furnace having front, rear and side walls, the combination with a stoker, of fluid cooled sections for said side and rear walls adjacent said stoker, said sections comprising a pair of headers mounted exteriorly of said front wall, a third header mounted intermediate said rear 40 wall, a series of fluid conducting tubes extending rearwardly from each of said first mentioned headers and lying in substantially abutting relation with the inner surfaces of said side walls, said tubes being bent near their rearwardly disposed ends so as to lie in abutting relation with a portion of the inner surface of said rear wall, 45 said tube terminating in said third header, means provided on said tubes and third header protecting the same against the abrasive and corrosive 50 action of the fuel fed by said stoker, and means for circulating a cooling medium through said tubes and headers.

55 7. In a furnace, having front, rear and side walls, the combination of fluid cooled sections 60 for said side and rear walls comprising, a pair of headers mounted exteriorly of said front wall, a downwardly and rearwardly inclined header mounted intermediate the ends of said rear wall, and a series of fluid conducting tubes extending 65 rearwardly from each of said first mentioned headers and lying in substantially abutting relation with the inner surfaces of said side walls, said tubes being bent near the rearwardly disposed ends thereof, and extend transversely of 70 and in substantially abutting relation with the inner surface of a portion of said rear wall, the said last mentioned portions of said tubes being arranged in a downwardly and rearwardly inclined series 75

8. In a furnace having front, rear and side walls, the combination of fluid cooled sections for said side and rear walls comprising, a pair of headers mounted exteriorly of said front wall, a downwardly and rearwardly inclined header 5 mounted intermediate the ends of said rear wall, a series of fluid conducting tubes extending rearwardly from each of said first mentioned headers and lying in substantially abutting relation with the inner surfaces of said side walls, said tubes 10 being bent near the rearwardly disposed ends thereof, and extend transversely of and in substantially abutting relation with the inner surface of a portion of said rear wall, the said last mentioned portions of said tubes being arranged 15 in a downwardly and rearwardly inclined series from top to bottom, said tubes terminating in said third header, and protective means for said tubes and headers.

20 9. In a furnace, having front, rear and side walls, the combination of fluid cooled sections for said side and rear walls comprising, a pair of headers mounted exteriorly of said front wall, a downwardly and rearwardly inclined header 25 mounted intermediate the ends of said rear wall, a series of fluid conducting tubes extending rearwardly from each of said first mentioned headers and lying in substantially abutting relation with the inner surfaces of said side walls, said tubes being bent near the rearwardly disposed ends 30 thereof, and extend transversely of and in substantially abutting relation with the inner surface of a portion of said rear wall, the said last mentioned portions of said tubes being arranged in a downwardly and rearwardly inclined series 35 from top to bottom, said tubes terminating in said third header, protective means for said tubes and headers, and means for circulating cooling medium through said tubes and headers.

40 10. In a furnace, having front, rear and side walls, the combination with an inclined grate, multiple retort underfeed stoker, of fluid cooled sections for said side and rear walls adjacent said stoker, said sections comprising a pair of substantially vertically disposed headers mounted 45 exteriorly of said front wall, a third header mounted in said rear wall intermediate the ends thereof, a series of fluid conducting tubes extending rearwardly from each of said first mentioned headers and lying in substantially abutting relation with the inner surfaces of said side walls, said tubes being disposed in substantially parallel relation with said stoker, and the lower portions thereof being bent, so as to extend transversely of a portion of said rear wall, 50 and said tubes terminating in said third header.

55 11. In a furnace having front, rear and side walls, the combination with a stoker, of fluid cooled sections for said side and rear walls adjacent said stoker, comprising a pair of headers 60 mounted exteriorly of said front wall, a downwardly and rearwardly inclined header provided in the lower portion of said rear wall intermediate said side walls, and a series of fluid conducting tubes extending rearwardly from each of said first mentioned headers and lying in substantially abutting relation with the inner surfaces of said side walls, said tubes being bent through substantially 90 degrees near their rearwardly disposed ends, and lying in substantially 65 abutting relation with a portion of the inner surface of said rear wall, and said tubes terminating in said third header, the rearwardly disposed portions of said tubes being arranged in a downwardly and rearwardly inclined series 70

75

from top to bottom, and the said fluid cooled portion of said rear wall being arranged in spaced relation with the rearwardly disposed end of the stoker forming a discharge passage for the refuse fed from the stoker therebetween, and means for varying the size of said passage.

12. In a furnace, having front, rear and side walls, the combination with an inclined grate, multiple retort underfeed stoker, of fluid cooled sections for said side and rear walls adjacent said stoker, the said fluid cooled section for the rear wall inclining downwardly and rearwardly and overlying a portion of the lower end of said stoker and forming therewith a passage for the refuse fed from said stoker, said fluid cooled sections comprising a pair of headers mounted exteriorly of said front wall, a downwardly and rearwardly inclined header in said rear wall, and a series of fluid conducting tubes extending rearwardly and downwardly from each of said first mentioned headers in substantially parallel relation with said stoker, and lying in abutting relation with the inner surfaces of said side walls, the lower portions of said tubes being bent so as to extend transversely over a portion of the inner surface of said rear wall and terminating in said last mentioned header.

13. In a furnace, having front, rear and side walls, the combination with an inclined grate, multiple retort underfeed stoker, of fluid cooled sections for said side and rear walls adjacent said stoker, the said fluid cooled section for the rear wall inclining downwardly and rearwardly and overlying a portion of the lower end of said stoker and forming therewith a passage for the refuse fed from said stoker, said fluid cooled sections comprising a pair of headers mounted exteriorly of said front wall, a downwardly and rearwardly inclined header in said rear wall, a series of fluid conducting tubes extending rearwardly and downwardly from each of said first mentioned headers in substantially parallel relation with said stoker, and lying in abutting relation to the inner surfaces of said side walls, the lower portions of said tubes being bent so as

to extend transversely over a portion of the inner surface of said rear wall and terminating in said last mentioned header, means for feeding the refuse through said passage, and fluid conducting means mounted in cooling relation with the grates of said stoker.

14. In a furnace, having front, rear and side walls, the combination with an inclined grate, multiple retort underfeed stoker, of fluid cooled sections for said side and rear walls adjacent said stoker, the said fluid cooled section for the rear wall inclining downwardly and rearwardly and overlying a portion of the lower end of said stoker and forming therewith a passage for the refuse fed from said stoker, said fluid cooled sections comprising a pair of headers mounted exteriorly of said front wall, a downwardly and rearwardly inclined header in said rear wall, a series of fluid conducting tubes extending rearwardly and downwardly from each of said first mentioned headers in substantially parallel relation with said stoker, and lying in abutting relation with the inner surfaces of said side walls, the lower portions of said tubes being bent so as to extend transversely over a portion of the inner surface of said rear wall and terminating in said last mentioned header, fluid conducting means mounted in cooling relation with said front wall, and said last mentioned means extending downwardly over the grates of said stoker and in cooling relation therewith.

15. In a furnace, having front, rear and side walls, the combination of fluid cooled sections for said side and rear walls comprising, a pair of headers mounted exteriorly of said front wall, a third header mounted intermediate the ends of said rear wall, a series of fluid conducting tubes extending rearwardly from each of said first mentioned headers in substantially parallel relation with said side walls, said tubes being bent near their rearwardly disposed ends so as to lie in substantially parallel relation with said rear wall, and said tubes terminating in said third header.

CHARLES L. MYERS. 45
